Amaziah Whitney (assignor of S. H. Parsons) Albany N.Y.
Letters Patent (Design No. 105) dated January 5th 1845
ante dated 6th July 1846

The Schedule referred to in these Letters Patent and making
part of the same.

To all whom it may concern; Be it known that I, Amaziah
Whitney, of Albany, in the County of Albany and State of New York,
have invented or produced a new ornamental design for an air tight
stone, and I do hereby declare that the following is a full, clear, and

exact account of the same, reference being had to the accompanying drawings making part of this specification in which Fig. 1 is a perspective view of a stone after my design and Figs. 2, 3, 4, & 5, are detached portions upon a larger scale to show the detail of ornaments. The body of my stone is intended to be of sheet iron - the horizontal section being an ellipse - Fig. 3 represents a portion of the enriched moulding surrounding the cap, or top, and Fig. 4, that about the base. Fig. 2 is a section of the former, and 6 of the latter moulding. Fig. 3 shows the register, the portion left blank in the figure being filled with repetitions of the parts represented - Fig. 5 represents a portion of the mouldings around the door - The ornamental figures are not easily describable in words, but are fully represented in the drawings.

What I claim as my invention and desire to secure by letters patent, is the combination and arrangement of ornamental figures herein described and shown, forming an ornamental design for an air tight stone.
